UNITED STATES PATENT OFFICE.

MARTIN L. BRAMHALL, OF LA PORTE, INDIANA.

WEATHER-STRIP.

SPECIFICATION forming part of Letters Patent No. 284,602, dated September 11, 1883.

Application filed April 24, 1883. (No model.)

To all whom it may concern:

Be it known that I, MARTIN L. BRAMHALL, of La Porte, La Porte county, and State of Indiana, have invented certain new and useful 5 Improvements in a Weather-Strip, of which the following is a full, clear, and exact description, that will enable others to make and use the same, reference being had to the accompanying drawings, and to letters of reference 10 marked thereon, forming a part of this specification.

This invention relates more especially to an improved weather-strip to be used on doors, but may be so modified as to be applied to 15 windows; and it consists of certain novel features in the construction and arrangement of the parts, as will be hereinafter more fully set forth.

Figure 1 is an elevation of a door embodying 20 my improved feature; Fig. 2, a broken-away vertical transverse section of the lower end of the same. Figs. 3, 4, and 6 are sectional details, showing the construction and arrangement of the mechanism connecting and controlling the adjustment of the weather-strip as 25 the door is opened or closed. Fig. 5 is a view of the plate set on the top of the weather-strip for the attachment of the inner end of the operating-levers.

Referring to the drawings, A A' represents 30 the door jambs or posts; A², the door; A³, an ordinary knob-lock. The lower end of the door is provided with a central rectangular recess, B, which receives the weather-strip. 35 This recess is of some considerable depth and extends the whole width of the door, the bottom of the recess being of an irregular outline, as shown in Fig. 2 of the drawings.

The weather-strip consists of the wooden 40 strip B' and the rubber strip B², attached to the under side of the same. The upper side of the strip B' is provided with the metal plates a a', which are duplicates of each other, one of them being shown in Fig. 5. These plates 45 are attached to strip B' by means of the screws a² a³, and are provided with the elongated apertures a⁴, having the outer ends enlarged for the insertion of the head of the tap-bolt b, inserted in the under side and back end of the lever C C'. The strip B' is provided with the

elongated recess or recesses b⁶, which correspond to the apertures in the plates a a', and allow the tap-bolt b to have a movement longitudinally therein. The levers C C' are duplicates, the outer ends being formed with the bifurcated 55 ends or arms d d' d² d³, as shown in Fig. 2 of the drawings. The ends of the lower arms, d d', are provided with the pins b' b², which have bearings in the staples b³ b⁴, that pass through and rigidly secure the lower ends of the flat 60 springs D D' to the metal plates C C', attached to the front and back edges of the door. The upper arms, d' d³, are secured to the thickened 65 ends of the springs D D' by means of the screw-bolt b⁵.

The inner end of the beveled catch D², recessed into the front edge of the door, is attached to the outer side of the spring D by the screw-bolt d⁵, as shown in Fig. 6. The catch D² does not engage with a recess or become locked 70 when the door is closed, but performs the function of throwing the inner end of the lever C downward, imparting a corresponding movement to the weather-strip. The catch D² strikes against the curved plate a⁵, attached 75 to the jamb A, which form causes a gradual downward movement of the weather-strip.

The upper outer side of the spring D', attached to the lever C', is provided with the bolt F, which projects from the back edge of 80 the door when open, but is gradually forced inward by contact with the jamb when the door is closing. The springs D D' serve to return the parts to their normal position when the door is opened, as shown in Fig. 2 of the 85 drawings, the dotted lines indicating the opposite position assumed when the door is closed.

The outer ends of the operating-levers, being something after the form of a bell-crank, have a somewhat similar action, the precise operation 90 being as follows: As the door is being closed the bolt F at the back edge of the door is gradually forced inward by frictional contact with the jamb, which movement, through the medium of the lever C', first throws this end of 95 the weather-strip down on the saddle of the threshold, this being accomplished gradually as the door closes, and as the catch, actuating the lever C at the front edge of the door, in turn comes in contact with the curved strik- 100

ing-plate attached to the jamb, this end of the weather-strip is gradually moved down to a close bearing on the saddle. The tension of the springs D D' may be regulated by shortening or lengthening the bolts having frictional contact with the door-jams. By this arrangement the weather-strip is automatically adjusted, is up out of the way and out of sight when the door is opened, and contact with the saddle is so gradual that the wear is slight, and it is not liable to get out of order or to be torn away.

Having thus described my invention, what I claim as new, and desire to secure by Letters Patent, is—

1. The combination, with the wood strip B', supporting the elastic strip B², of the companion levers C C', the slotted plates a a', the springs D D', the catch D², the striking plate a⁵, and

the projecting bolt F, all combined, arranged, 20 and operating substantially as set forth.

2. The combination, with the strip B', provided with the recess b⁶, of the metal plates a a', provided with the elongated apertures a⁴, substantially as described. 25

3. The combination, with a weather-strip recessed in the under side of a door, of the companion levers C C', the springs D D', the catch D², and the bolt F, whereby said weather-strip is automatically and gradually brought 30 in contact with the saddle of the threshold when the door is closed and drawn up out of the way when the door is opened, substantially as and for the purpose set forth.

MARTIN L. BRAMHALL.
